**STABILIZED SELENIUM DISULFIDE
THERAPEUTIC SHAMPOO**

Maynard M. Baldwin and Amps P. Young, Jr., Columbus, Ohio, assignors, by mesne assignments, to Abbott Laboratories, North Chicago, Ill., a corporation of Illinois

No Drawing. Application January 7, 1953;
Serial No. 330,174

12 Claims. (Cl. 167—87)

This invention relates to therapeutically useful stable compositions containing active selenium disulfide, and to a method for preparing said stabilized formulations.

This application is a continuation-in-part of our pending application Serial No. 39,196, filed July 16, 1948, and now abandoned.

Selenium disulfide has great potential therapeutic and fungicidal value, and in the active form it is the product obtained by processes such as those described in U. S. Letters Patent Nos. 1,860,154 and 1,860,336 to B. W. Nordlander. It is, however, not useful by itself in compositions for biological purposes, because the disulfide is not wet readily, as intimate association of moisture is required for the full realization of its activity. It is, therefore, necessary to incorporate the disulfide with a hydrophilic material, such as bentonite. Although it would appear that selenium disulfide and bentonite do not form a true chemical compound, it is believed that this association is more than an intimate mixture. For convenience, these solid, hydrophilic, selenium disulfide compositions are designated as "sesols," and a method for accomplishing this association is described in B. W. Nordlander's U. S. Letters Patent No. 1,860,320.

Thus, sesols are of value as the active constituents in suspensions, pastes, ointments, shampoos, and the like, for treating abnormal skin conditions, and in the form of dusts and suspensions for controlling fungus diseases of plants. Sesol compositions are particularly effective for controlling dandruff.

When formulated in the usual aqueous media, however, it has been found that the sesol is adversely affected on extended storage under normal temperature conditions, and, also, on exposure to elevated temperatures and light. These adverse effects are evidenced by a marked color change of the sesol, accompanied by a decrease in its effectiveness in treating abnormal skin conditions and fungi, increase in the difficulty of removal, by washing, from the scalp and absorptive material and the appearance of skin irritating effects.

It is an object of this invention to provide a method for stabilizing sesols in aqueous media so that they can be maintained in a suitable active state during adverse exposure conditions.

It is another object of this invention to provide a composition of matter containing sesol which has been stabilized.

It is a further object of this invention to provide a method for producing formulations having stabilized sesol therein.

It has now been found that sesols in contact with aqueous media can be stabilized by the addition of sufficient water soluble, acidic material to the sesol compositions to render the resulting compositions acidic. Over a long period of time under temperature conditions these acidic, sesol compositions maintain their characteristic yellow-orange color and their therapeutic properties.

It has also been found that selenium disulfide is exceptionally good as a treatment for scalp disorders such as dandruff. We have now discovered a composition containing selenium disulfide which may be readily removed from the scalp after the treatment in order that it does not discolor the hair or cause irritation of the skin. In preparing such a shampoo, we have found that it is necessary to employ a detergent along with the aqueous hydrophilic selenium disulfide suspension. The detergent serves the purpose of removing the selenium disulfide suspension from the scalp and hair following the treat-

2

ment therewith, and effectively prevents any irritation which might develop from prolonged contact of selenium disulfide with the skin.

The term "detergent" is used herein in its ordinary sense to mean a cleansing agent which is capable of removing foreign particles along with washing. The exact nature of the detergent will be disclosed in greater detail in the examples, but it is sufficient to note at this time that all three of the major classes of detergents may be satisfactorily employed in a shampoo of the type described herein. That is, we may use anionic, cationic, and non-ionic detergents. The detergent must be compatible with selenium disulfide under the acidic conditions employed in preparing and stabilizing the suspension. By "compatible" is meant that the detergent does not affect the stability of selenium disulfide, does not accelerate the normal breakdown of the selenium disulfide, and does not cause any physical or chemical change which would result in rendering the selenium disulfide inactive or less-active on the skin. A marked color change is indicative of incompatibility and resultant instability in the selenium disulfide and the color change, or lack thereof, may be determined easily by one skilled in the art by subjecting formulations to the stability test described in the examples.

As suitable detergents we may mention the anionic detergents of the alkylaryl sulfonate type such as Nacconol NRSF and Santomerse D, and alcohol sulfate detergents such as sodium lauryl sulfate and triethanolamine lauryl sulfate. We have also found that the alkyl phosphate salts are suitable anionic detergents for the purposes of this invention. As cationic detergents which we have found satisfactory may be listed the sulfosuccinamate detergents such as n-octadecyl diisodium sulfosuccinamate and the corresponding tetrasodium sulfosuccinamate. These materials are marketed by American Cyanamid under the trade-name Aerosol. As compatible detergents we have found the fatty amines of the type represented by Alkanine S. J. (marketed by Amalgamated Chemical Company). We have also found that the hexitol oleates such as anhydrohexitol partial oleate marketed under the name Arlacel A (Atlas Powder Company) are suitable non-ionic detergents.

Considering the detergents in another way we have found that foaming or lathering detergents are particularly suitable for this invention since they combine both detergency and good foaming properties which assist in removing the selenium disulfide from the skin. The voluminous foam or lather produced by these detergents is also important from a consumer acceptance standpoint. In this class may be placed the alkyl aryl sulfonates and the alcohol sulfates. While a high degree of foaming or lathering is to be regarded favorably it should be remembered that foam is not necessarily an index of detergency and a suitable shampoo can be prepared by using a detergent which gives a small volume of foam or no foam at all. The anhydrohexitol partial oleates, the sulfated fatty amines, n-octadecyl sodium sulfosuccinamates, and alkyl phosphate salts give fair to poor foams but are excellent detergents and wash away easily from the skin and hair, taking with them the selenium disulfide suspension. These poor to fair foaming detergents may be used in conjunction with an auxiliary foam producing material such as the inorganic phosphate salts, the modified polyoxyethylene esters, long-chain amides, cellulose derivatives, and sequestering agents. They may also be used in conjunction with foaming or lathering detergents.

Suitable water soluble acidic materials for stabilizing these sesol suspensions are inorganic and organic acids, or their acid salts, or mixtures of these acids with their acid salts. Examples of these acidic materials are hydrochloric, sulfuric, phosphoric, acetic, propionic, lactic, citric, tartaric, and succinic acids, and monosodium phosphate, sodium citrate, and sodium tartrate acid salts. The solid acids and their acid salts may be added to the sesol mixture as solids or liquids solutions, although it facilitates matters to add them in solution.

Excellent results have been obtained by adding sufficient acidic materials to the aqueous media to obtain a pH of between about 2 and 6.6. In other words the pH of the system must be on the acid side, but need not be highly acidic. It will be noted from the following ex-

amples that the stability of the selenium disulfide suspension depends to a certain extent upon the pH of the aqueous suspension. At any rate, pH's on the alkaline side should be avoided, because the shelf life of the commercial products will be adversely effected.

The following examples will serve to illustrate the invention with more particularity:

Example 1

Suspensions of a sesol were prepared by mixing the sesol with an aqueous solution of an alkyl-aryl sulfonate surface-active or wetting agent, the resulting suspension having a pH of about 8. One suspension showed marked color changes after only 18 hours at 60° C., in a constant temperature bath, without the addition of any acidic materials. Another suspension but with sufficient citric acid added to bring the pH down to 3.3, showed no appreciable color change during a period of over 650 hours at 60° C.

Example 2

A suspension of a sesol was prepared by mixing the sesol with an aqueous solution of an alkyl-aryl sulfonate surface-active or wetting agent containing one per cent mono-sodium phosphate as the only acidic material added. The resulting suspension had a pH value of above 5 and it changed color appreciably after 48 hours at 60° C.

Example 3

Suspensions of a sesol were made in water and found to have a pH of 8 or above. The pH values of the sesol suspensions were then adjusted by the addition of citric acid to provide suspensions having different pH values. These suspensions were next subjected to a temperature of 60° C. in a constant temperature bath for extended period of time. Stability of the selenium disulfide in the sesol was indicated by persistency of the characteristic yellow-orange color of the sesol. The following results were obtained:

Adjusted pH of Composition	Approx. No. of Hours at 60° C. Without Appreciable Color Change
9.3	18
7.7	18
6.1	42
4.6	360
3.8	360
3.7	360
2.9	360
2.5	360

Example 4

Suspensions of a sesol were prepared by mixing the sesol with an aqueous solution of an alkyl-aryl sulfonate surface-active or wetting agent containing a small amount of monosodium phosphate, the resulting suspension having a pH of above 5. The pH of these suspensions were then adjusted by the additions of various amounts of citric acid solution. As before, the suspensions were placed in a 60° C. constant temperature bath, and their color stability was observed. The following results were obtained:

Adjusted pH of Composition	Approx. No. of Hours at 60° C. Without Appreciable Color Change
5.6	100
5.5	100
5.3	100
4.9	100
4.7	500
4.6	670
4.2	2,600
4.0	4,400

Example 5

An experiment similar to that of Example 4 was performed with suspensions that contained various amounts of acetic acid in place of the citric acid. The following results were obtained:

Adjusted pH of Composition	Approx. No. of Hours at 60° C. Without Appreciable Color Change
4.0	120
3.6	120
3.2	264

Example 6

An experiment similar to that of Example 4 was run using various amounts of sulfuric acid solution in place of citric acid to adjust the pH. The following results were obtained:

Adjusted pH of Composition	Approx. No. of Hours at 60° C. Without Appreciable Color Change
5.5	24
4.7	144
3.3	672

The above examples clearly point out that an aqueous, sesol suspension in water, or water to which has been added only a wetting agent, shows a marked color change after 18 hours. If the suspension contained a wetting agent and also an acid salt, the color did not change for 48 hours. Where an acid alone was used in the sesol suspension, the color did not change for over 360 hours, and if the suspension contained an acid and a wetting agent, the color did not change for over 650 hours. The maximum observed period, over 4400 hours, was shown where the sesol suspension contained an acid, an acid salt, and a wetting agent. It will be understood that, while the acid salt plus the acid provide good stabilization, an acid by itself also effects good stabilization. Excellent results were obtained where the suspension contained, in addition to the acid, an acid salt and a wetting agent.

Example 7

A preferred composition of selenium disulfide for use as a shampoo is represented by the following formula:

Per cent w./v.
Composition of equal parts of selenium sulfide and bentonite
Bentonite
Monobasic sodium phosphate
Glyceryl monoricinoleate
Alkyl aryl sulfonate
Citric acid
Perfume
Water, q. s. to

The bentonite is wetted with water and the alkyl aryl sulfonate is added and dissolved with stirring. Then glyceryl monoricinoleate and monosodium phosphate are similarly added and stirred in. After the solution has become uniform the selenium sulfide-bentonite powder is added in small amounts and stirring is continued until a uniform suspension is obtained. Then citric acid is added in a quantity sufficient to adjust the pH of the composition to about 4.5. The perfume is added and stirred in and water is added to bring up to volume. This product has a shelf life in excess of one year.

Example 8

The formulation shown in Example 7 is repeated substituting 17% weight by volume of sodium lauryl sulfate for the alkyl aryl sulfonate. The product obtained by this formulation washed away from the skin and hair very readily and produced large quantities of lather. The product is quite satisfactory as a shampoo. Upon aging for one month at 40° C. the product showed no color change.

Example 9

The formulation shown in Example 7 is repeated substituting 17% weight by volume of triethanolamine lauryl sulfate, technical, in place of the alkyl aryl sulfonate. This formulation was also a very satisfactory shampoo.

and was readily washed away with the formation of large quantities of lather and foam. The product was subjected to aging for one month at 40° C. and no change in color was observed.

Example 10

The formulation shown in Example 7 is repeated using an alkyl phosphate salt such as TLF 548 E Powder (Du Pont) or MPD 1936 B (Du Pont) in place of the alkyl aryl sulfonate in similar quantities. The pH of a suspension was adjusted to about 6.6 and the material was subjected to testing as a shampoo. A medium quantity of foam was obtained and the product washed away very readily from skin and hair. It appeared to have excellent properties as a detergent. The product passed the aging test of one month at 40° C. without color change.

Example 11

The formulation shown in Example 7 was repeated substituting an acid phosphate intermediate of an alkyl phosphate salt (MPD 2005 Du Pont) for the alkyl aryl sulfonate. Here again a good shampoo was obtained which produced a medium amount of foam and seemed to have excellent washing properties. The pH of the suspension was adjusted to 2.5. This product also meets the aging test of one month at 40° C. without color change.

Example 12

The formulation shown in Example 7 was repeated substituting for the alkyl aryl sulfonate a cationic detergent of the type represented by n-octadecyl disodium sulfosuccinamate. This product produced a fair amount of foam which was comparatively small as compared to the amount produced by the alkyl aryl sulfonates and alcohol sulfates. The product was very easy to wash away, however, and exhibited excellent detergent properties. It met the aging test of one month at 40° C. without color change.

Example 13

The formulation shown in Example 7 was repeated substituting n-octadecyl tetrasodium (1-2-dicarboxyethyl sulfosuccinamate) for the alkyl aryl sulfonate. Here again only a fair amount of foam or lather was produced upon testing of the product, but the material was quite satisfactory as a detergent and was easy to wash away. This detergent is a cationic detergent. The shampoo met the test of one month at 40° C. without color change.

Example 14

The formulation shown in Example 7 was repeated using a non-ionic detergent as represented by the sulfated fatty amine, Alkamine S. J. (Amalgamated Chemical Company), in place of alkyl aryl sulfonate. A fair amount of foam or lather was produced, but the material was an excellent detergent and the shampoo washed away easily taking with it all of the selenium disulfide suspension. This shampoo met the aging test of one month at 40° C. without color change.

Example 15

The formulation shown in Example 7 was repeated using the non-ionic anhydrohexitol partial oleates (Arlacel A—Atlas Powder Company) as detergent in place of the alkyl aryl sulfonate. In this instance only a small amount of foam was produced by the shampoo, but the shampoo showed excellent detergent properties and washed away easily taking with it the suspension of selenium disulfide. This material also passed the aging test of one month at 40° C. without color change.

Example 16

A composition was prepared as represented by the following formula:

	Per cent w./v.
Composition of equal parts of selenium sulfide and bentonite	5.0
Bentonite	4.0
Glyceryl monoricinoleate	1.0
Citric acid	0.2-0.5
Perfume	0.5
Anhydrohexitol partial oleate	13.0
Monobasic sodium phosphate	2.0
Water q. s. to	100

In this formulation a detergent was employed which produced only a relatively small quantity of foam or lather in itself. The detergent was, however, quite suitable for removing the suspension of selenium disulfide from the hair and scalp. In order to enhance the foaming qualities and thereby produce a product which would have greater consumer acceptance, an auxiliary foaming agent, monosodium phosphate was added.

- The stabilized sesol in aqueous media may be used 10 in the manufacture of liquid, paste, and oil-in-water emulsion shampoos, and in liquids, pastes, and ointments having remarkable skin treating properties. The stabilized sesol composition may be incorporated in the shampoo base, or the sesol may be added to the shampoo base 15 and then stabilized. This later method has been used to produce a shampoo which maintained its yellow-orange color at 60° C. over 4400 hours.

In summary it will be appreciated that this invention 20 discloses a very easy method for stabilizing sesols in aqueous media. The term "aqueous media," as used herein, is understood to include emulsions, pastes and other sesol compositions of varying viscosity in which water forms an integral part. The use of well-known, 25 economically obtained acids permits the ready production of formulations containing sesol which have long shelf-life. Such formulations maintain their characteristic yellow-orange color for extended periods of time as well as their useful therapeutic and fungicidal qualities. Thus, 30 this stabilization of the sesol formulations greatly enhances their commercial value, saleability, and widespread employment.

We claim:

1. A shampoo composition comprising an alkyl-aryl sulfonate, an aqueous suspension of activated stabilized hydrophilic selenium disulfide and sufficient of an acidic substance to adjust the pH between about 3 and about 5.
2. A shampoo composition comprising an alkyl-aryl sulfonate, an aqueous suspension of activated stabilized hydrophilic selenium disulfide and sufficient of an acid to adjust the pH between about 3 and about 5.
3. A shampoo composition comprising an alkyl-aryl sulfonate, an aqueous suspension of activated stabilized hydrophilic selenium disulfide and sufficient of an acid salt to buffer the pH between about 3 and about 5.
4. A shampoo composition comprising an alkyl-aryl sulfonate, an aqueous suspension of activated stabilized hydrophilic selenium disulfide and sufficient of an acid salt and an acid to buffer the pH between about 3 and about 5.
5. A shampoo composition comprising an alkyl-aryl sulfonate, an aqueous suspension of activated stabilized hydrophilic selenium disulfide composed of selenium disulfide and bentonite and sufficient of an acidic substance to adjust the pH between about 3 and about 5.
6. A shampoo composition comprising an alkyl-aryl sulfonate, an aqueous suspension of activated stabilized hydrophilic selenium disulfide composed of selenium disulfide and bentonite and sufficient of an acid to adjust the pH between about 3 and about 5.
7. A shampoo composition comprising an alkyl-aryl sulfonate, an aqueous suspension of activated stabilized hydrophilic selenium disulfide composed of selenium disulfide and bentonite and sufficient of an acid salt to buffer the pH between about 3 and about 5.
8. A shampoo composition comprising an alkyl-aryl sulfonate, an aqueous suspension of activated stabilized hydrophilic selenium disulfide containing selenium disulfide and bentonite and sufficient of an acid salt and an acid to buffer the pH between about 3 and about 5.
9. A shampoo composition comprising a stable aqueous suspension of activated stabilized hydrophilic selenium disulfide, sufficient of an acidic substance to adjust the pH between about 2 and about 6.6, and a detergent.
10. A shampoo composition comprising a stable aqueous suspension of activated stabilized hydrophilic selenium disulfide, sufficient of an acidic substance to adjust the pH between about 2 and about 6.6, and a lathering detergent.
11. A shampoo composition comprising a stable aqueous suspension of activated stabilized hydrophilic selenium disulfide, sufficient of an acidic substance to adjust the pH between about 2 and about 6.6, a detergent, and a foam producing material.
12. A shampoo composition comprising a stable aqueous suspension of activated stabilized hydrophilic selenium disulfide, sufficient of an acidic substance to

adjust the pH between about 2 and about 6.6, and an alcohol sulfate detergent.
